CLAIM

We claim, the ornamental design for an operating/display panel, as shown and described.

DESCRIPTION

FIG. 1 is a perspective view of an operating/display panel, showing our new design in a first embodiment;

FIG. 2 is a front view thereof;

FIG. 3 is a rear view thereof;

FIG. 4 is a side view thereof;

FIG. 5 is another side view thereof;

FIG. 6 is a top view thereof;

FIG. 7 is a bottom view thereof;

FIG. 8 is another perspective view thereof, as shown mounted to a wall in a user environment; and,

FIG. 9 is another side view thereof, as shown mounted to a wall in a user environment.

The broken lines as shown in the Figures are included for the purpose of illustrating portions of the “article” and forms no part of the claimed design.

1 Claim, 7 Drawing Sheets(56)
